UNITED STATES PATENT OFFICE.

FRANK W. EVERETT, OF BROOKLINE, MASSACHUSETTS, ASSIGNOR TO SWEET-NUT BUTTER CO., OF BOSTON, MASSACHUSETTS, A CORPORATION OF MASSACHUSETTS.

DESIGN FOR A DISPLAY DEVICE.

53,361.

Specification for Design.

Patented May 27, 1919.

Application filed November 29, 1918. Serial No. 264,747. Term of patent 14 years.

To all whom it may concern:

Be it known that I, FRANK W. EVERETT, a citizen of the United States, residing at Brookline, in the county of Norfolk and Commonwealth of Massachusetts, have invented a new, original, and ornamental Design for a Display Device, of which the following is a specification, reference being had

to the accompanying drawing, forming part thereof.

The figure is a face view of a display device, showing my new design.

I claim:—

The ornamental design for a display device, as shown.

FRANK W. EVERETT.
